UNITED STATES PATENT OFFICE

131,356

DESIGN FOR A SKIMMING SPOON

Joseph Woginrich, Walnutport, Pa.

Application October 10, 1941, Serial No. 103,718

Term of patent 7 years

To all whom it may concern:

Be it known that I, Joseph Woginrich, a citizen of the United States, residing at Walnutport, in the county of Northampton and State of Pennsylvania, have invented a new, original, and ornamental Design for a Skimming Spoon, of which the following is a specification, reference being had to the accompanying drawing, forming part thereof.

I claim:

The ornamental design for a skimming spoon, as shown.

JOSEPH WOGINRICH.
